US0D1056501S

(12) United States Design Patent (10) Patent No.: US D1,056,501 S
(45) Date of Patent: * Jan. 7, 2025

(54) DRAWER ORGANIZER

(71) Applicant: Drawer Solutions Inc., Minneapolis, MN (US)

(72) Inventor: Andrew Wilson, Minneapolis, MN (US)

(73) Assignee: Drawer Solutions Inc., Minneapolis, MN (US)

() Term: 15 Years

(21) Appl. No.: 29/840,606

(22) Filed: May 31, 2022

(51) LOC (15) Cl. 07-09

(52) U.S. Cl.

USPC D7/637; D3/313

(58) Field of Classification Search

USPC D3/304, 305, 306, 307, 308, 309, 310,

D3/311, 312; D7/555, 550.1, 553.1, 637

CPC A47B 88/90; A47B 88/969; A47B 88/994;

B65D 1/36

(57) CLAIM

The ornamental design for the drawer organizer as shown and described.

DESCRIPTION

FIG. 1 is a perspective view of a first embodiment of a drawer organizer;

FIG. 2 is a front view thereof;

FIG. 3 is a right side view thereof;

FIG. 4 is a top view thereof;

FIG. 5 is a rear view thereof;

FIG. 6 is a left side view thereof;

FIG. 7 is a bottom view thereof;

FIG. 8 is a perspective view of a second embodiment of a drawer organizer;

FIG. 9 is a front view thereof;

FIG. 10 is a right side view thereof;

FIG. 11 is a top view thereof;

FIG. 12 is a rear view thereof;

FIG. 13 is a left side view thereof;

FIG. 14 is a bottom view thereof;

FIG. 15 is a perspective view of a third embodiment of a drawer organizer;

FIG. 16 is a front view thereof;

FIG. 17 is a right side view thereof;

FIG. 18 is a top view thereof;

FIG. 19 is a rear view thereof;

FIG. 20 is a left side view thereof; and,

FIG. 21 is a bottom view thereof.
